United States Patent Office

Des. 183,547
Patented Sept. 16, 1958

183,547

ROOF FOR AN AUTOMOBILE

Clifford C. Voss, Clawson, Mich., assignor to Chrysler Corporation, Highland Park, Mich., a corporation of Delaware

Application July 29, 1957, Serial No. 47,123

Term of patent 14 years

(Cl. D14—27)

FIG. 1

FIG. 2

FIG. 6

FIG. 3

FIG. 4

FIG. 5

Fig. 1 is a top plan view of a roof for an automobile;
Fig. 2 is a side elevational view thereof;
Figs. 3, 4 and 5 are sectional views taken on the lines
3—3, 4—4 and 5—5, respectively, of Fig. 2; and

Fig. 6 is a side elevational view of an automobile showing my new design.

The dominant features of my design reside in the portions shown by means of full lines in the drawings.

I claim:

The ornamental design for a roof for an automobile, substantially as shown and described.
